UNITED STATES PATENT OFFICE.

JOHN P. HOTZ, OF NEWTON, MASSACHUSETTS.

DESIGN FOR A TRAFFIC-SIGNAL.

58,673.

Specification for Design.

Patented Aug. 9, 1921.

Application filed February 28, 1921. Serial No. 448,604. Term of patent 7 years.

To all whom it may concern:

Be it known that I, JOHN P. HOTZ, a citizen of the United States, residing at Newton, in the county of Middlesex and State of Massachusetts, have invented a new, original, and ornamental Design for Traffic-Signals, of which the following is a specification, reference being had to the accompanying drawings, forming a part thereof.

In the drawings:

Figure 1 is a plan view of a traffic signal showing my new design.

Fig. 2 is a front elevation of said traffic signal.

Fig. 3 is an end elevation of the traffic signal as viewed from the right of Fig. 2.

I claim:

The ornamental design for a traffic signal as shown.

In testimony whereof I have hereunto set my hand in presence of two subscribing witnesses.

JOHN P. HOTZ.
